INDUSTRIAL CLAMP

Vitas T. Thomas, Robert A. Lovdahl, Edward J. Lazzeroni, Salvatore F. Aiello, and Bruce L. Renquist, Racine, Wis., assignors to Tomco, Inc., Racine, Wis., a corporation of Wisconsin

Filed Apr. 8, 1968, Ser. No. 11,350

Term of patent 14 years

Int. Cl. D8—03

U.S. Cl. D54—1

FIG. 1 is a left front perspective view of an industrial clamp.

FIG. 2 is a top plan view of the clamp.

FIG. 3 is an elevational view of the left side of the clamp.

FIG. 4 is an elevational view of the back of the clamp.

FIG. 5 is an elevational view of the front of the clamp.

FIG. 6 is a bottom plan view of the clamp. The right side of the clamp is a complement of the left side.

The dominant features reside in the solid line portions. We claim:

The ornamental design for an industrial clamp, as shown and described.
